UNITED STATES PATENT OFFICE.

WILLIAM E. KLECKNER, OF HICKSVILLE, OHIO.

AXLE-NUT WRENCH.

SPECIFICATION forming part of Letters Patent No. 570,933, dated November 10, 1896.

Application filed March 6, 1896. Serial No. 582,124. (No model.)

To all whom it may concern:

Be it known that I, WILLIAM E. KLECKNER, a citizen of the United States, residing at Hicksville, in the county of Defiance and State 5 of Ohio, have invented certain new and useful Improvements in Axle-Nut Wrenches; and I do declare the following to be a full, clear, and exact description of the invention, such as will enable others skilled in the art to which 10 it appertains to make and use the same.

This invention relates to an axle - nut wrench, and it contemplates improving such devices by providing a cheap and effective means whereby the nut will be removed from 15 the axle-spindle by simply turning the wheel backwardly, applied by reversing the direction of movement of the wheel, and the device itself will remain in engagement with the wheel when the latter has been removed 20 from the spindle, and will in turn hold the nut in proper position within the wheel-band.

The invention and its many advantages will appear from the following description and claims when taken in connection with the 25 annexed drawings, in which—

Figure 1 is a longitudinal sectional view through a wheel-hub and my improvements applied thereto. Fig. 2 is a sectional view taken in the plane indicated by the dotted 30 line *x x* on Fig. 1. Fig. 3 is a sectional view taken at right angles to Fig. 2 and at the point indicated by the dotted line *y y* on Fig. 1, and Fig. 4 is a perspective view of my device with the parts separated and the operating-screw removed.

Referring by letter to said drawings, A indicates a wheel-hub, B indicates an axle-spindle, and C indicates a nut, all of which may be of the form and construction usually 40 employed. Such parts constitute no part of my invention, but are here shown simply for the purpose of illustrating the application of my improved device.

D indicates the hub-band, which may be also 45 of the character usually employed.

My improved wrench comprises a stationary or fixed jaw *a* and a slidable jaw *b*. The stationary jaw has an angular socket *c*, composed of the end wall *d* and the lateral walls 50 *e*. On the outer side of the wall *d* is fixed or formed thereon the lug or branch *f*, which is screw-tapped transversely at a suitable dis-

tance from its outer end and in the longitudinal plane of the device, as shown at *g*. The angular socket, or "nut-seat," as I shall designate it, has an open wall, as shown, and extending horizontally from this open side or wall is a slide branch *h*, which is designed to receive the slidable jaw *b*, the latter being slotted for the purpose, as shown at *i*. This 60 slidable jaw, as well as the fixed jaw, is beveled on its outer side, as shown, so as to snugly engage the inner side of the hub-band at opposite points, as will be presently described. The slidable jaw is of a width slightly less 65 than the width of the nut socket or seat, so that it may partly enter said socket or close the open side thereof. This jaw is also provided at its opposite or lower end with an aperture *j* for the purpose of receiving one 70 end of the operating-screw *E*, which latter has its bearing in the screw-tapped aperture *g* of the lug or branch *f*. This operating-screw, which takes through said threaded lug or branch, is provided at one end with a cross-bar or handle *k* for the grasp of the operator, and its opposite end is here shown as reduced 75 and shouldered at *l*, and the reduced portion is passed through the aperture *j* of the slidable jaw and secured by means of a pin *m* 80 and a washer *n*.

It is obvious that the screw may be swiveled or connected loosely to the slidable jaw by other means, and I do not wish to confine myself to the particular construction shown 85 for the purpose.

I provide two opposite walls of the socket or nut-seat with friction-springs *F*, which are here shown as composed of flat spring metal and curved so as to permit the nut to readily 90 enter and hold the same from casual displacement.

In operation when it is desired to remove a wheel from its axle or spindle the screw should be turned so as to draw in the slidable jaw sufficient to permit the jaws to enter within the band *D* of the hub and receive the nut. The screw should then be turned so as to force outwardly the slidable jaw and bring the outer side into frictional contact with the 95 inner side of the hub-band. By then rotating the wheel backwardly it will be seen that the nut will be screwed off from the spindle, but by reason of the device being fixed to the 100

hub-band the wheel, the device, and the nut will all remain intact. To replace the wheel, it is simply necessary to turn it forwardly or in a reverse direction, and after the nut has 5 been screwed home by then manipulating the screw of the device, so as to release the jaws from contact with the hub-band, said device may be removed from the wheel.

It will thus be seen that I have a very convenient wrench for removing and replacing axle-nuts, and one which may be manufactured at a small expense and used without soiling the hands of the operator.

Having described my invention, what I 15 claim is—

1. The axle-wrench comprising the fixed jaw carrying the nut seat or socket, and having the lug or branch provided with the screw-tapped aperture, and the slidable branch extending therefrom, the slidable jaw arranged 20 on said slidable branch, and both jaws adapt-

ed to engage the inner side of a hub-band, and the operating-screw connecting said jaws, substantially as specified.

2. The fixed or stationary jaw having its 25 outer side beveled and carrying the nut seat or socket provided with friction-springs, and having the lug or branch provided with the screw-tapped aperture *g*, and also having the slidable branch or bearing *h*, the slidable jaw 30 *b*, having the slot *i*, and also beveled on its outer side, and the screw *E*, bearing in the threaded aperture *g*, and secured at one end in the aperture *j*, of the slidable jaw, substantially as specified.

In testimony whereof I affix my signature in presence of two witnesses.

WILLIAM E. KLECKNER.
